UNITED STATES PATENT OFFICE.

ALBERT G. ELVIN, OF SOMERVILLE, NEW JERSEY.

MECHANICAL STOKER.

1,111,531.

Specification of Letters Patent. Patented Sept. 22, 1914.

Application filed February 24, 1913. Serial No. 750,124.

To all whom it may concern:

Be it known that I, ALBERT G. ELVIN, of Somerville, in the county of Somerset and State of New Jersey, have invented a certain new and useful Improvement in Mechanical Stokers, of which improvement the following is a specification.

My invention relates to appliances for feeding fuel to locomotive and other steam boiler furnaces, in which the members which act directly upon the fuel are in the form of fuel carrying and throwing shovels, moving about vertical axes, adjacent to a firing opening in the furnace, as generally exemplified in Letters Patent of the United States No. 1,058,356, granted and issued to me under date of April 8, 1913.

The object of my present invention is to provide means, of simple and inexpensive construction, for imparting movement to the shovels of a mechanical stoker of the above type, in proper reciprocal relation and at the speed proper in different portions of their traverse for the performance of their function of feeding fuel to the furnace.

The improvement claimed is hereinafter fully set forth.

In the accompanying drawings: Figure 1 is a rear view, partly in elevation and partly in section on the line *a a* of Fig. 2, of a mechanical stoker embodying my invention, attached to the back head of a locomotive boiler; Fig. 2, a horizontal section on the line *b b* of Fig. 1; Fig. 3, a plan or top view; Fig. 4, a vertical longitudinal central section; Fig. 5, a side view, in elevation, and on an enlarged scale, of the operating cam; and, Fig. 6, a transverse section through the same, on the line *c c* of Fig. 5.

My invention is designed and adapted for operation in connection with a suitable source of fuel supply, a conveyer for transferring fuel therefrom to a location of deposit adjacent to a firebox, and an elevator for raising the fuel therefrom to a level at which the action of the mechanism herein-after set forth for projecting it into the firebox can be properly exerted upon it. Instances of these appliances are exemplified in Letters Patent No. 1,058,356 aforesaid, and these, or any other suitable appliances of such character, may be employed in connection with my present invention. These, however, do not constitute part thereof, and will not, therefore, be herein at length described.

In the practice of my invention, I provide a shovel box or casing, 9, which is bolted at its front end to, and supported by, a bracket, 9^a, secured to the rear head of a firebox, *b*, and is supplied with fuel in any suitable known manner. The forward side of the shovel box is fully open to the firing opening, *b'*, of the firebox, near the lower side of said opening, so as to leave as much as possible of the upper portion thereof unobstructed, said upper portion being closed by firing doors, 10, of the ordinary construction. By the usual manipulation of said doors by a hand lever, 10^a, manual firing can be operated, if it should, at any time, become necessary or desirable to intermit the operation of the mechanism of my invention.

The fuel which is supplied to the shovel box is gathered up therein, in successive portions or charges, and carried forward and projected into the firebox, *b*, through the firing opening, *b'*, by swinging movements of two fuel carrying and throwing shovels, each comprising a stock or body, 11, and a blade, 11^a, of stout sheet metal, which is curved longitudinally and curved or bent transversely, thereby enabling the shovel to receive and carry in its movements, a charge of fuel, in the manner of an ordinary fireman's shovel or scoop. The shovels, 11, 11^a, are fixed upon the squared upper ends of two shovel shafts, 12, the axes of which are located on opposite sides of the shovel box, in a transverse plane thereof, perpendicular to its bottom plate, which plate may be either horizontal or slightly inclined, as may be deemed best adaptable to the position of the rear head of the firebox, which in some cases is vertical, and in others, forwardly and upwardly inclined. The axes of the shovel shafts may therefore be stated to be located in a substantially vertical plane. In the outward or feeding traverses of the shovels, in each of which they carry a charge of fuel, they are swung comparatively rapidly, and their inward or return traverses are effected comparatively slowly. The mechanism by which the shovels are so operated will now be described.

A segmental spur gear, 12^a, is fixed upon each of the shovel shafts, below the bottom of the shovel box, said gears engaging corresponding gears, 25^a, fixed on the upper ends of two intermediate shafts, 25, which are journaled, parallel with the shovel shafts, in bearings, 26, on a frame, 27, fixed to the

bottom of the shovel box. The intermediate shafts, 25, carry, adjacent to their lower ends, segmental spur gears, 25^a, each of which engages a rack, 28, fitted to reciprocate in a horizontal guide, 29, on the adjacent side of the frame, 27. A roller, 30, is journaled on a stem fixed in the inner side of each of the racks, 28, said rollers engaging a peripheral groove, 31^a, in an operating cam, 31, which is fixed on a horizontal cam shaft, 32, mounted in bearings, 33, on the bottom of the frame, 27, the axial line of said shaft being located parallel with, and midway between, the pitch lines of the racks, 28. The rollers, 30, are provided for the purpose of reducing friction in the engagement of the racks with the cam groove, which engagement could, of course, be directly effected, if desired, by fitting the stems of said rollers 20 in the groove. The cam shaft is rotated by a small motor (not shown), which is located in any convenient position adjacent to the boiler head, and may desirably be of the type set forth in Letters Patent of the 25 United States No. 1,050,528, granted and issued to me under date of January 14, 1918, or may be of any other suitable and preferred form, and which does not form part 30 of my present invention. In the instance shown, rotation is imparted to the cam shaft through a chain, 34^a, engaging the teeth of a sprocket, 34, fixed upon the cam shaft, and a similar sprocket on the driving shaft of the motor.

As will clearly appear by reference to Figs. 5 and 6 of the drawings, the cam groove, 31^a, is formed in the cam in such angular relation to the axis thereof that the major portion of said groove, as say, about two thirds of its projected length, is perpendicular to said axis; a relatively shorter portion of the remainder of its projected length is inclined, relatively to said major portion; and a relatively longer portion of the remainder of its projected length extends, with an opposite inclination, and at a lesser angle, from said smaller portion to the major portion first specified. It therefore follows that, in the rotation of the cam, a member engaged with the cam groove will remain stationary while the portion of said groove which is perpendicular to the axis of the cam is passing it; will be moved in one direction, comparatively rapidly, while the shorter inclined portion is passing it; and will be moved in the opposite direction, comparatively slowly, while the longer inclined portion is passing it, the periods of rest, of relatively quick movement in one direction, and of relatively slow movement in the opposite direction, being successive, in the order stated.

In the operation of a mechanical stoker embodying my invention, a proper supply of fuel being delivered to the shovel box, and

the motor of the cam shaft being rotated at such speed as will effect the rate of firing desired, each member of the pair of shovels will, through the operating cam and the intermediate connections described, be swung 70 from the rear to the front terminal of its stroke, with comparative rapidity, effecting its outward stroke, in which it will gather, upon the horizontal portion of its blade, a charge of fuel, carry said charge forwardly, 75 and throw it into and toward one side of the firebox. It will then be returned, comparatively slowly, to the rear terminal of its stroke, in readiness for a succeeding similar operation. During the described movements 80 of one of the shovels, the other shovel will be intermediately connected with the portion of the cam groove which is perpendicular to the axis of the cam, and will remain 85 stationary. When the shovel first referred to has reached the rear terminal of its stroke, the other shovel will, by the rotation of the cam, be brought, successively, into connection with the longer and the shorter inclined portions of the cam groove, and 90 will be swung first forwardly and then rearwardly, similarly to the shovel first described, and will similarly operate, except that it will throw the fuel toward the opposite side of the firebox. The alternate operations of the shovels will continue during the rotation of the motor, and the supply of fuel to the firebox may be regulated as desired by variations of the speed of the motor. 95

Among the practical advantages attained by my invention, there may be enumerated its adaptability for application, within small compass, and in connection with any preferred form of fuel conveying, elevating, and delivering mechanism, for service with any of the various forms of steam boiler and other fireboxes or furnaces; its structural and operative simplicity and inexpensiveness; and the connection of a pair of fuel carrying and throwing shovels with an actuating motor in such manner that the traverses of each of them will be effected in proper sequence, at greater and less speeds when feeding and returning, respectively, and without the possibility of interference 110 of one of them with the other.

I claim as my invention and desire to secure by Letters Patent:

1. In a mechanical stoker, the combination of a shovel shaft movable about a vertical axis, a fuel shovel fixed on said shaft, a rotatable grooved operating cam, a rack fitted to reciprocate parallel with the axis of said cam and engaging the groove thereof, an intermediate shaft parallel with the shovel 125 shaft, and gearing connecting said intermediate shaft with the rack and with the shovel shaft, respectively.

2. In a mechanical stoker, the combination of a receptacle, two shovel shafts, inde- 130

- pendently movable about vertical axes in said receptacle, two shovels, each fixed on one of said shafts, a rotatable grooved operating cam journaled intermediate of and at a right angle to the shovel shafts, under said receptacle and in rear of said shafts, members fitted to reciprocate parallel with and on opposite sides of the axis of the cam, each engaging the groove thereof, and intermediate connections independently transmitting movement from said members to the shovel shafts.
3. In a mechanical stoker, the combination of two shovel shafts, independently movable about vertical axes, two fuel shovels, each fixed on one of said shafts, a rotatable grooved operating cam journaled intermediate of and at a right angle to the shovel shafts, members fitted to reciprocate parallel with and on opposite sides of the axis of the cam, each engaging the groove thereof, and intermediate connections independently transmitting movement from said members to the shovel shafts.
4. In a mechanical stoker, the combination of two horizontally swinging shovels mounted on vertical shafts at opposite sides of the furnace opening, a rotatable cam cylinder having a groove with inclined portions in its periphery, racks having projections engaging said groove, and intermediate gear mechanism between said racks and the shovel shafts. 25
5. In a mechanical stoker, the combination of two horizontally swinging shovels mounted on vertical shafts at opposite sides of the furnace opening, a rotatable cam cylinder having a peripheral groove with one portion inclined at a comparatively steep angle and another portion inclined in the opposite direction at a lesser angle, racks having projections engaging said groove, and intermediate gear mechanism between said racks and the shovel shafts. 30
